(57) **CLAIM**

The ornamental design for a theft deterrent apparatus having a removable pin, as shown and described.

DESCRIPTION

FIG. 1 is a front perspective view of the theft deterrent apparatus having a removable pin in an engaged state;

FIG. 2 is a front plan view of the apparatus in an engaged state;

FIG. 3 is a left plan view of the apparatus in an engaged state;

FIG. 4 is a right plan view of the apparatus in an engaged state;

FIG. 5 is a top plan view of the apparatus in an engaged state;

FIG. 6 is a bottom plan view of the apparatus in an engaged state;

FIG. 7 is a left side plan view of the removable pin portion wherein the right side is a mirror image;

FIG. 8 is a front plan view of the body of the apparatus in an unengaged state;

FIG. 9 is a rear plan view of the apparatus;

FIG. 10 is a right rear perspective view of the apparatus in an engaged state; and,

FIG. 11 is a left rear perspective view of the apparatus in an engaged state.

The body and removable pin portions have been shown separately in FIGS. 7 and 8 for convenience of illustration.

In the drawings, the broken lines illustrate environmental matter, and form no part of the claimed design.
